UNITED STATES PATENT OFFICE.

EDWARD E. GRAY, OF PLANO, ILLINOIS.

GEAR-SHIFTING MECHANISM.

1,175,145.

Specification of Letters Patent. Patented Mar. 14, 1916.

Application filed April 6, 1914. Serial No. 829,759.

To all whom it may concern:

Be it known that I, EDWARD E. GRAY, a citizen of the United States, residing at Plano, in the county of Kendall and State 5 of Illinois, have invented certain new and useful Improvements in Gear-Shifting Mechanism, of which the following is a specification.

This invention relates to mechanism for shifting gears, more particularly described 10 as fluid pressure gear shifting mechanism as used in connection with motor vehicles, although, of course, it may have a more general application.

The principal object of the invention is to provide an improved form of gear shifting mechanism operated by fluid pressure, as set forth in my co-pending application Serial No. 708,761, filed in the United States 20 Patent Office on July 11, 1912, with a new form of operating valve therefor.

A further object of the invention is to improve the mechanism, as well as the valve, by means of which the shifting device is simplified, the operation of the same is rendered easier and its certainty in working is increased.

A further object of the invention is to provide means rendering it possible to give the 30 whole mechanism a compact construction and, should the fluid pressure medium fail to act, to change the gears by hand.

For the attainment of these ends and the accomplishment of other new and useful improvements, as will appear, the invention 35 consists in the features of novelty in the construction, combination and arrangement of the several parts generally shown in the accompanying drawings and described in the specification, but more particularly pointed out in the appended claims.

In the drawings: Figure 1 is a side elevation, parts being shown in section, of the general arrangement of the shifting mechanism; Fig. 2 is a sectional view showing the cylinder and valve connection; Fig. 3 is a side view on a larger scale of the combined control and inlet valve; Fig. 4 is a plan view of Fig. 3; Fig. 5 is a section on line 6—6 50 of Fig. 3, and Fig. 6 is a section on line 5—5 of Fig. 3.

A special feature of the invention consists in the formation of the controlling mechanism and the control valve by means of which it is possible that on moving the control valve body in one direction, the inlet

valve is opened and closed to effect the admission of fluid under pressure to the control cylinder, whereas, on the return of the control valve body the inlet valve is not effected. 60

Referring now more particularly to the drawings, a valve casing 1 is formed with a cylindrical bore 2 for containing a longitudinally movable valve spindle 3, a cylindrical bore 4 for a piston 5, and with an opening 6 for the inlet valve 7, which opening 6 is in communication with the valve spindle bore 2. The control valve bore 2 is connected by means of ducts 8 and 9 with the front and back cylinder ends and there are further provided discharge ducts 10 and 11 forming communication between control valve bore 2 and a common discharge duct 12, rendering possible the exhaust of the expanded pressure medium from the cylinder 70 at both ends thereof.

The spindle 3 is provided at its rear end with an enlargement 13 and a bearing portion 14 upon which is disposed a spiral 80 spring 15 tending to press a shoulder 16 of a nut 35 attached to the front end of the spindle, against the valve casing and to thus hold the control valve in its normal position. That portion of the spindle between the bearing portion 14 and the nut 35 is formed with circular grooves 17^a, 17^b, 17^c, 17^d, and 17^e of various widths whereby disks 18^a, 18^b, 18^c, 18^d, and 18^e are formed, which fit accurately into the valve spindle bore 2. Circular grooves are so arranged and their width is such that the corresponding disks of the control valve spindle 3 effect an opening and closing of the ducts 8 and 9 leading to the front and rear cylinder ends, and also the 85 engagement of a bell crank 19 pivotally mounted in the opening 6. The inlet valve 7 is provided with a member 20 slidable in a perforation through the stem thereof and having a head 30 at the inner end adapted 100 to be engaged by one extremity 27 of the bell crank 19, the other extremity 26 of which is adapted to be engaged by the disks of the control valve 3. This bell crank 19 is pivotally mounted in an elongated hole 105 21 on a pin 22 in the opening 6, and to it is connected a spring 23 which tends to pull the bell crank so that the extremity 27 engages the head 30 of the member 20 and so that the other extremity 26 is in position to 110 be engaged by any one of the disks on the control valve 3.

A rod 24 is connected by means of a slotted connection to a pedal 25 which controls the operation of a clutch 25^a adapted to be held in engagement by a clutch spring 25^b, so that the forward movement of the clutch pedal first releases the clutch then when the lost motion connection is taken up moves the control valve spindle 4 forwardly by means of the rod 24.

10. The gear selecting and operating mechanism comprises a rotatable selecting spindle 28 connected by means of rods 29, 30, pinion 31, segment 32 and rod 33 with an indicating arm 34 movable over a segment 35. A 15 piston sleeve 36 extends from the bore 4 through the front of the casing 1 where a control plate 37 is secured which is splined to the spindle 28. This control plate 37 is provided with a recess 38 in which is 20 mounted a dog 39 pressed outwardly by a spring 40. The control plate 37 is provided with an outer ring 41 which forms an annular groove 42 into which, upon the failure of the fluid pressure device, a lever or the 25 like can be inserted in order to change the gear by hand.

Arranged peripherally with respect to the control plate 37 are gear shifting rods 43, 44, and opposite the rods 43 are stub shafts 30 45 adapted to be connected therewith by pinions 46. Each of the rods 43, 44 and the stub shafts 45 are formed with a shoulder 47 adapted to be engaged by the plate 37 and with a groove 48 in front of the shoulder adapted to be engaged by the dog 39. In front of the groove 48 of the rods 43 and 44 is a depression 49 substantially the length of stroke of the piston 5 so that even if the piston and the control plate 37 is at the 40 forward end of its stroke the dog 39 may be freely rotated by means of the spindle 38 without engaging any of the rods 43 or 44. Upon the rearward movement of the control plate 37 the dog 39 will ride upon an 45 inclined surface 50 on one of the rods or upon an inclined surface 51 at the end of one of the stub shafts 45. This construction is for the purpose of permitting the rotation of the spindle 28 even though one of the 50 rods 43 or 44 has been moved into position for changing the gear ratio.

Connected to the inlet valve 7 by means of a pipe 52 is a fluid pressure reservoir 53. A hand valve 54 may be inserted in the pipe 55 for manually controlling the fluid under pressure from the reservoir and for preventing the escape of fluid under pressure from the reservoir.

In operation the pedal 25 is moved down- 60 wardly, and, as before explained, after the clutch is disengaged the lost motion connection with the rod 24 is taken up, the control valve spindle 23 is moved forwardly until the duct 8 is connected by means of the 65 groove 17^b with the opening 6. The forward

movement of the spindle engages the ridge 18^d with the projecting extremity 26 of the bell crank 19, moving it about its pivot 22 to open the valve 7 against the pressure of the valve spring. This action admits fluid under pressure through the duct 8 to the forward end of the cylindrical bore 4 thereby causing the piston 5 to be moved rearwardly, carrying with it the plate 37, which, in its rearward movement, engages the shoulders 47 of all of the control rods, returning any and all of them to neutral position. At this time the rear end of the cylindrical bore 4 is connected by means of the duct 9 and the cylindrical groove 17^e of the valve spindle with the discharge ducts 11 and 12 thereby opening the rear of the cylindrical bore to exhaust. It will be noted that the ridge or disk 18^d is comparatively narrow so that as soon as it has passed from engagement with the extremity 26 of the bell crank, the latter will ride in the groove 17^d and the valve 7 will be closed by its valve spring. The continued movement of the control valve spindle 3 in a forward direction will bring the ridge 18^e into engagement with the bell crank 19, at which time the forward end of the cylindrical bore is connected by means of the duct 8, and the groove 17^b with the discharge ducts 10 and 12, opening the forward end of the cylindrical bore to exhaust. Communication is also made at this time with the rear end of the cylindrical bore by means of the duct 9 and the groove 17^e with the opening 6 so that as the bell crank rides on the ridge 18^e the valve 7 will be opened, admitting air to the rear end of the cylindrical bore and forcing the piston forwardly, at which time the dog 39 actually engages any one of the 10 selected rods 43, 44 or the stub shafts 45. Upon raising the foot from the pedal 25 the clutch spring 25^b operates to return the pedal to its normal position, whereupon the valve spindle 3 is also returned by means 11 of the spring 15. Upon the rearward movement of the valve spindle the engagement of the various disks or ridges with the extremity 26 of the bell crank will produce no 12 effect upon the valve 7 for the reason that the bell crank 19 will be pressed inwardly against the tension of its spring 23 because of the elongated hole 21 by means of which it is pivoted. It is obvious, therefore, that the changes in the connection of the cylindrical bore 4 with the source of pressure supply are effected entirely upon the forward movement of the valve spindle and that the rearward movement thereof has no effect upon the valve. The selection of any 12 gear for operation may be made at any time by means of the arm 34 or other equivalent mechanism even when the mechanism is connected with another gear in actual operation, the shifting of the gears being effected 13

by first returning all of the gear changing members to neutral position, as just explained, and then by effecting the desired movement of the member for moving the selected gear.

5 What I claim is:

1. Gear shifting mechanism comprising change speed gears shiftable into driving engagement, fluid pressure means for shifting the gears comprising a bodily movable control valve member, and an operating member therefor having a lost motion connection.

10 2. In gear shifting mechanism comprising change speed gears, the combination of a fluid pressure device for shifting the gears, and a control valve for the device comprising a movable valve member for operatively actuating the device in only one direction of movement.

20 3. Gear shifting mechanism comprising change speed gears, a fluid pressure device for shifting the gears, and a control valve for the device comprising a valve member for actuating the device in one direction of movement and ineffective in the other direction of movement.

30 4. In gear shifting mechanism, the combination with change speed gears, of a fluid pressure device for changing the gears, an inlet valve for the device, and a control valve comprising a longitudinally movable member, and means contacting with the member for operating the inlet valve.

35 5. The combination with gear shifting mechanism comprising change speed gears, of a single fluid pressure device for actuating the same, an inlet valve and a control valve forming communication between the inlet valve and the fluid pressure device having a longitudinally movable member adapted to make connection between the inlet valve and the device in one direction of movement, and means actuated by the member for operating the inlet valve in one direction of movement only of said member.

40 6. In fluid pressure gear shifting mechanism, a control valve therefor comprising a longitudinally movable valve spindle, an inlet valve, ducts communicating with the fluid pressure device, and a member actuated by the movement of the spindle in one direction for opening the inlet valve ineffective in the other direction of movement of the spindle to operate the inlet valve.

45 7. In fluid pressure gear shifting mechanism, an operating valve comprising a casting with a cylindrical bore, a grooved spindle longitudinally movable therein, an inlet valve communicating with the bore, ducts forming communication between the bore and the fluid pressure device, means to move the spindle longitudinally, and a member having an elongated slot by which it is

pivoted adapted to engage the spindle and the inlet valve for opening the latter when the spindle is moved in one direction and for moving rearwardly in the slot when the spindle is moved in the other direction.

70

8. In fluid pressure gear shifting mechanism, the combination with a fluid pressure device comprising a member with cylindrical bores, a piston movable in one of the bores, a grooved spindle movable in the other bore, ducts connecting the spindle bore with the ends of the other bore, a fluid pressure inlet communicating with the spindle bore, and means for moving the spindle in one direction whereby the grooves will first admit fluid under pressure from the inlet to one end of the cylinder bore and then to the other end of the cylinder bore while the spindle is moving in a single direction.

85

9. Fluid pressure gear shifting mechanism comprising a member formed with cylindrical bores, one of which is connected at both ends with the other, and the other of which is provided with discharge ports and with an inlet opening, of a spindle movable in the said other bore having grooves therein and ridges which fit in the bore, and means for moving the spindle whereby in one direction of movement communication is made first between the inlet and one end of the cylindrical bore while the other end is open to exhaust, and by the continued movement of the spindle in the same direction the first named end of the cylindrical bore is open to exhaust and the other end to fluid pressure from the inlet opening.

95

10. Fluid pressure gear shifting mechanism comprising a member formed with cylindrical bores, one of which is connected at both ends with the other, and the other of which is provided with discharge ports and with an inlet opening, of a spindle movable in the said other bore having grooves therein and ridges which fit in the bore, and means for returning the spindle member.

105

11. The combination with a fluid pressure gear shifting mechanism comprising a controlling valve therefor having a longitudinally movable valve control member, of change speed gears adapted to be placed in different driving engagements by the fluid pressure device, driving means for the change speed gears embodying a releasable clutch and a spring therefor, a pedal to control the operation of the clutch, and means comprising lost motion connection for connecting the pedal to the valve control member whereby the movement of the pedal in one direction will release the clutch and then operate the valve control member.

115

12. In fluid pressure gear shifting mechanism, fluid pressure control means comprising a cylindrical valve chamber with fluid

125

130

pressure ducts, discharge ducts, an inlet opening communicating therewith, a valve spindle having peripheral grooves therein forming ridges between them and fitting the bore closely, an inlet valve communicating with the inlet opening, a bell crank having a slot and pivotally mounted thereby in the inlet opening with one end adapted to engage the ridges of the spindle and the other end adapted to engage the valve for opening it when the other end is engaged by the spindle in one direction of movement, means for moving the spindle in one direction whereby communication is made from the inlet opening first with one of the fluid pressure ducts and then with the other at which time the inlet valve is opened by the bell crank at the same time making connection between the correspondingly opposite fluid pressure opening and the discharge opening, and means to withdraw the valve spindle in the other direction when the said moving means is released.

13. In fluid pressure gear shifting mechanism, fluid pressure control means comprising a member with a control valve bore having inlet and discharge ducts and an inlet opening communicating therewith, a longitudinally movable valve spindle formed with peripheral grooves forming ridges thereon of different widths, the grooves being adapted to make connection in succession between the inlet opening and one of the inlet ducts and then the other when the spindle is moved in one direction and between the other inlet opening and the discharge opening and then between the first named inlet opening and the discharge opening in succession and oppositely when the spindle is moved in one direction, an inlet valve communicating with the inlet opening and having a projecting stem, a bell crank with a slotted hole by means of which it is pivoted, one end of the bell crank contacting with the inlet valve stem, the other extremity being adapted to be engaged by the ridges of the valve spindle for moving the bell crank to engage and open the inlet valve when the spindle is moved in one direction, the slot permitting the bell crank to ride over the ridges when the spindle is moved in the other direction, a spring tending to draw the bell crank to one end of its slot and to hold one extremity in position to be engaged by the ridges of the spindle with the other end in engagement with the valve stem, means to move the valve spindle in the forward or operating direction, and a spring to move the valve spindle in the opposite direction.

14. In combination, gear shifting mechanism comprising change speed gears, means for shifting some of the gears comprising

rods movable in both directions having engageable shoulders and notches, fluid pressure means comprising a member with bores, one forming a power cylinder and the other forming a valve chamber, the said member being provided with passages extending from the valve chamber to each end of the power cylinder, with other passages extending from the valve chamber and with an inlet opening communicating with the valve chamber, a piston provided with means for engaging the shoulders in one direction of movement, and with a spring-pressed tongue for engaging the notches formed on said gears in the other direction of movement, selecting means for rotating the tongue to engage any one of the bars at any time, a valve spindle formed with grooves and movable in the valve chamber, the grooves being adapted to form communication from the inlet opening to the front end of the cylinder and from the rear end of the cylinder to exhaust when moved in one direction and in another position when moved in the same direction to form communication from the forward end of the cylinder to exhaust and from the inlet opening to the rear end of the cylinder, an inlet valve disposed in the inlet opening, a bell crank pivotally mounted in the opening through a slotted perforation having one extremity adapted to engage the inlet valve and the other extremity to engage the ridges of the control spindle, the slot being so disposed that the movement of the spindle in one direction will raise the inlet valve and in the other direction of movement of the spindle the bell crank will ride over the projections, a spring tending to press the bell crank in engagement with the spindle, another spring tending to hold the spindle at one end of its stroke, means for driving the change speed gears comprising a releasable clutch and a clutch spring, a pedal adapted to release the clutch upon the forward movement thereof, and a rod connected to the valve spindle having a lost motion connection with the pedal whereby the movement of the pedal first releases the clutch then moves the valve to return the gear shift bars to neutral by the action of the piston in the cylinder, and then by the continued movement of the pedal in the same direction moves the piston forwardly in engagement with the previously selected rod.

In testimony whereof I have signed my name to this specification, in the presence of two subscribing witnesses, on this 18th day of March A. D. 1914.

EDWARD E. GRAY.
